CLAIMThe ornamental design for an electrode for a semiconductor
processing apparatus, as shown and described.**DESCRIPTION**FIG. 1 is a front elevational view of an electrode for a
semiconductor processing apparatus showing my new
design;FIG. 2 is a right side elevational view thereof; a left side
elevational view being a mirror image thereof;FIG. 3 is a top plan view thereof; a bottom plan view being
a mirror image thereof;

FIG. 4 is a rear elevational view thereof;

FIG. 5 is an enlarged cross-sectional view taken along line
5—5 of FIG. 1; and,FIG. 6 is an enlarged cross-sectional view taken along line
6—6 of FIG. 1.
